CLAIM

The ornamental design for a magnetic holding strap, as shown and described.

DESCRIPTION

FIG. 1 is a perspective view of a magnetic holding strap, showing my new design in a state of use;

FIG. 2 is a front perspective view thereof;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in FIGS. 2 and 4 represent portions of the magnetic holding strap and form no part of the claimed design.

1 Claim, 9 Drawing Sheets(56)
